CLAMP DEVICE FOR HAIR TINTING

Gertrude M. Hoffman, Omaha, Nebr.

Application November 7, 1941, Serial No. 418,175

17 Claims. (Cl. 132—9)

This invention relates to new and useful improvements in clamp devices for hair tinting.

One of the objects of my invention is to provide simple, efficient and adjustable clamping means whereby comparatively thin strands of tinted or dyed human hair may be tightly clampingly engaged and readily adjustably supported upon the head to conveniently permit the portions of the new growth of hair in such strand, near the roots of the hair, to be tinted or dyed to compensate for such growth subsequent to the initial dyeing of the hair.

Another object of my invention is to provide such adjustably-supported clamping means in the form of pairs of cooperating bars of non-porous and non-absorbing material, preferably resilient material such as rubber, although non-absorbent fiber may be used, or other suitable plastic composition. Such bars being preferably elongated and of both straight and slightly arcuate shapes, and including clamps for tightly clamping together each pair of the strand-supporting bars to thereby prevent seepage therebetween of the dyeing solution onto the portion of the strand of the dyed hair which is clamped between such bars so that the new growth of hair near the roots may be neatly dyed without streaking and without double-tinting portions of the originally tinted hair which is securely held between the bars; such bars, and clamps therefor, and their adjustable supports being preferably of a rubber or fiber composition which is not effected by the dye or tinting solution to thereby obviate any chemical reaction or undesirable effect upon the hair, in other words, for practical purposes, I prefer to make most of the parts of my improved device of non-metallic material and where metallic parts are used to impart strength, such metallic parts may preferably be coated with rubber or with a pressed fiber composition which is not effected by or non-reactive to dyes.

Another feature of my invention is found in the undulating formation of the complementary clamping faces of the strand-supporting bars whereby the strand of hair is not only more securely retained but the wavy form of the bar faces facilitates the tinting operation.

Other novel features of my invention are found in the screw-adjustable supports for the strand-supporting bars; in the novel wedge-like clamps; and in the novel flexible adjustable means for interconnecting a plurality of spaced sets of the strand-retaining bars to thereby retain same upon the head during the tinting and drying of the hair strand.

With the above and other objects in view which will readily become apparent from the perusal of the following specification and attached drawing, my invention consists in the novel combination, construction and arrangement of the parts and members shown in preferred embodiments in the attached drawings, described in the following specifications, and particularly pointed out in the appended claims.

10 In the drawings:

Fig. 1 is a side elevation of a clamp device for hair-tinting embodying my invention;

Fig. 2 is a half plan view and half longitudinal section taken on line 2—2 of Fig. 1;

Fig. 3 is a vertical cross-section taken on line 3—3 of Fig. 1;

Fig. 4 is a side elevation of a clamp device for hair-tinting embodying a modification of my invention;

Fig. 5 is a plan view of the clamp device shown in Fig. 4;

Fig. 6 is a vertical cross-section taken on line 6—6 of Fig. 4;

Fig. 7 is an end view of a rubber-covered resilient clamp which may be employed in the clamp device illustrated in Figs. 4, 5 and 6;

Fig. 8 is a side elevation of a clamp device for hair-tinting embodying another modification of my invention but showing one of the end clamps removed from the two strand-supporting bar members;

Fig. 9 is a plan view of the device shown in Fig. 8;

Fig. 10 is a top view of one of the clamps for the device shown in Figs. 8 and 9;

Fig. 11 is a vertical cross-section through the clamp shown in Fig. 10 taken on line 11—11 of Fig. 10;

Figs. 12 and 13 illustrate respectively plan view and side elevation of a pair of reenforced strand-supporting bars;

Figs. 14 and 15 illustrate respectively plan view and side elevations of a pair of interlocked strand-supporting bars; and

Fig. 16 illustrates my improved means for supporting a plurality of pairs of strand-supporting bars in relatively spaced positions during the drying of the dye.

Figs. 1 to 7 inclusive show my invention applied to pairs of strand-supporting bars of elongated arcuate shape, and Figs. 8 to 15 inclusive show my invention applied to pairs of strand-supporting bars of elongated but straight form.

The bars illustrated in Figs. 12 to 15 inclusive are adapted to be clampingly secured together by

clamps which are applied from opposite ends of the bars and which clamps are of the type illustrated in Figs. 1, 2, 3, 10 and 11.

In the illustrations, like reference characters indicate like or corresponding parts or members.

The embodiment of my invention illustrated in Figs. 1, 2 and 3 consist of a pair of elongated slightly arcuate bars 20 having preferably undulating adjacent inner contact faces 21 of complementary formation to interfit one another. The outer face of each bar 20 is formed with a pair of integral oppositely disposed wedge-like formations 22, each increasing in cross-sectional thickness toward the center of the bar, narrower in width than the width of the face of the bar 15 from which the formations project outwardly.

While the bars 20 are shown in slight arcuate formation somewhat conforming to the curve of the top of a human head, these bars 20 may be straight as shown in Figs. 8 to 15 inclusive, likewise, the hair strand clamping faces 21 may be plane-aligned surfaces 23 as shown in Figs. 14 and 15 although I prefer to use the slightly undulating contact faces 21.

As shown in Figs. 1 and 2, the strand of hair 24, which is to be dyed or tinted, is embodied between the undulating faces 21 of the bars 20 and the two bars are then tightly clamping secured together by the clamps 25 which are slidably moved over the wedge-like formations 22 inwardly from the ends of the bars 20 to thereby firmly press the bars 20 toward each other to tightly secure the strand of hair disposed between them and thus prevent seepage of the dye onto the dyed hair held between them.

Since the rate of growth of human hair is substantially uniform the bars 20 are so applied to the strand of hair that the line of the new growth is substantially aligned with the bottoms 20^a of the bars 20 to thus establish a guide for the operator performing the dyeing operation.

The clamps 25 are of U-shape and each clamp is formed with spaced arms 26 having channeled inner sides to fit the bar wedges 22, as shown in Fig. 3. The arms 26 are formed integrally with the back portion 27 which is threaded to receive an adjustable threaded screw support 28 having a knurled head 29 and the lower end rotatably connected with a supporting base 30.

To facilitate the tinting of the new growth of hair, the screws 28 are adjusted to extend the strand of hair 24 in raised or stretched position upon the spaced three-legged bases 30 which rest upon the head.

The screw 28 and base 30 may be made of metal but I prefer to make both of these parts of a highly compressed fiber composition.

From the above, the construction, operation and use of the device shown in Figs. 1, 2 and 3 will now be clearly understood.

The modified form of my invention illustrated in Figs. 4 to 7 inclusive consists of two strand-supporting bars 31 of trapeziform cross-section preferably provided with contact faces 21 of undulating formation.

The end surface portions of the outer faces being serrated or provided with a series of longitudinally extending tooth-like formations 32 to provide resistance to the upward movement of the two clamps 33 made of resilient metal 33^M embedded in molded rubber 33^R, as shown in Fig. 7, and having serrated portions 33^S.

The clamps 33 may also be made of metal, as shown in Figs. 4 to 6 inclusive, each clamp 33 consisting of a strip of spring steel formed into

a clamp of V-shaped cross-section having angularly flanged ends 33^A and having tooth-like formations 33^B formed on portions of the opposed inner faces.

When the strand of hair 24 is interposed between these two bars 31, the clamps 33 are forcibly mounted upon the serrated ends 32 to tightly engage the strand of hair disposed between their undulating inner faces. The resistance between the clamp teeth 33^B and the serrations 32 retains the clamps 33 in adjusted positions thereon and the clamp flanges 33^A form suitable supports for retaining the device upon the head. The resiliency of the clamps 33 permit their adjustment vertically relatively to the longitudinal axis of the two bars for proper alignment with the line of the untinted growth of hair.

The slightly modified form of the device illustrated in Figs. 8, 9, 10 and 11 is very similar in construction to that disclosed in Figs. 1, 2 and 3. The structural differences in the bars 34 consist in the straight formation of the bars 34 and in the provision of a vertically disposed threaded opening 35 at one end of each bar for the threaded adjustable support 28. The clamp 36 is simply made of stiff material of channeled cross-section bent into U-shaped form, as illustrated in Figs. 10 and 11.

The bars 34 shown in Figs. 12 and 13 are similar in construction to those shown in Figs. 8 and 9 except that these illustrations show the straight bars each reenforced with a thin strip 37 of resilient steel embedded in the body of hard rubber and these bars are adapted to be clamping engaged by the clamps 25 or the clamps 36.

The strand-engaging bars 38 illustrated in Figs. 14 and 15 are not shown reenforced, however, these bars and the bars shown in Figs. 1, 2, 4 and 5, could all be reenforced like the bars 34 shown in Figs. 12 and 13. My thought in showing the reenforcing strips is that the cross-section of the rubber may in such reenforced bars be somewhat reduced to afford the use of thinner bars or to strengthen the rubber body of the bars as shown in Figs. 12 and 13.

The bars 38 also differ from the bars shown in Figs. 12 and 13 in the formation of the plane-aligned contact faces 23 and in forming each 50 of the bars 38 with a transverse rib 39 near one end and with a transverse slot 40 near the other end. The rib and slot being formed on the inner or contact face and when the bars 38 are relatively reversed in mounted position, the rib 55 39 of each bar will fit into the slot 40 of the other bar to thus interlock the bars against relative longitudinal movement. In the other bar designs shown in Figs. 2, 5, 9 and 12, the opposed undulating faces prevent relative longitudinal displacement.

Multiple sets of the strand-supporting bars may be successively applied to and supported on a person's head until the dye has dried by the employment of suitable interconnecting members 65 which interconnect the multiple sets of bars and facilitate their retainment on the head. One type of such interconnecting member is illustrated in Fig. 16.

The interconnecting member consists of a pair 70 of spring-pressed clasps 41 each having a spring 42 urging the toothed-engaging ends 43 into gripping position with the strand-supporting bar member 44. The clasps 41 are interconnected with a pair of resilient metallic strips 45 each having one end secured to one of the clasps 41

and the opposite end in slidable embracement with the adjacent portion of the other strip 45.

The strips are relatively movable longitudinally to shorten or lengthen their span between the clasps 41.

It is obvious to those skilled in the art to which my invention appertains that the devices described and claimed herein are applicable to bleaching, ointment or tonic treatments as well as to dyeing of hair, and therefore, in each instance where the word "dyeing" is used, the same shall be construed to include bleaching, ointment or tonic treatments and that throughout the specification and claims the word "dyeing" or "tinting" is synonymous with bleaching, or ointment or tonic treatments.

It is also obvious that the particular details of construction and arrangement of the parts and members, shown in the drawings and described in the specification by way of illustration of preferred embodiments of my invention, may be varied without departing from the spirit of my invention which is defined in the appended claims.

I claim:

1. In a device for hair dyeing, a pair of bars of non-absorbent material adapted to engage a strand of hair between them, clamping means adapted to retain the adjacent faces of said bars in pressure-gripping engagement with the strand of hair to prevent seepage of the dye onto the portion of the strand retained between said bars and means for supporting said bars on a person's head.

2. In a device for hair dyeing, a pair of elongated bars of non-absorbent material adapted to engage a strand of hair between them, clamping means adapted to retain the adjacent faces of said bars in pressure-gripping engagement with the strand of hair, and supporting means disposed at the ends of said bars for supporting said bars on a person's head in spaced position above the scalp.

3. In a device for hair dyeing, a pair of elongated bars of non-absorbent material adapted to engage a strand of hair between them, clamping means at opposite end portions of said bars adapted to retain said bars in pressure-gripping engagement with the strand of hair to prevent seepage of the dye onto the portion of the strand retained between said bars, and adjustable means for supporting said bars on a person's head in a selectively spaced position above the scalp.

4. In a device for use in hair dyeing, a pair of elongated bars of non-absorbent material adapted to engage a strand of dyed hair between them to present the new growth of the undyed strand portion between the said bars and the scalp for dyeing thereof, clamps at the opposite end portions of said bars for retaining said bars in gripping engagement with the strand of hair to prevent seepage of the dye onto the portion of the strand retained between said bars, and adjustable supporting means at both ends of said pair of bars for supporting said bars on a person's head to thereby retain said undyed strand portion in stretched position to facilitate the dyeing thereof.

5. In a device for hair dyeing as embodied in claim 4, and including the adjacent faces of said pair of elongated bars each having an undulating surface formation, said undulating surfaces being disposed in complementary relatively interengaged arrangement.

6. In a device for hair dyeing as embodied in

claim 4, and including said pair of elongated bars having a slight arcuate form longitudinally thereof and each bar having an undulating inner face, said undulating faces being disposed in complementary relatively interengaged arrangement.

7. In a device for use in hair dyeing, a pair of elongated bars of non-absorbent material adapted to engage a strand of dyed hair between them to present the new growth of the undyed strand portion between the said bars and the scalp for dyeing thereof, the outer face of each of said bars having oppositely disposed wedge-like integral formations, a U-shaped clamp slidably forcibly mounted from each end of each pair of bars onto said wedge-like formations for clamping retaining said bars in gripping engagement with the strand of hair, and a screw-adjustable supporting member in threaded engagement with each of said clamps for adjustably supporting said bars on a person's head to thereby retain said undyed strand portion in stretched position to facilitate the dyeing thereof.

25 8. In a device for use in hair dyeing, a pair of elongated bars of non-absorbent material adapted to engage a strand of dyed hair between them to present the new growth of the undyed strand portion between the said bars and the scalp for dyeing thereof, a U-shaped clamp forcibly mounted from each end of said pair of bars for clamping retaining said bars in gripping engagement with the strand of hair, and an adjustable supporting member in threaded engagement with each of said clamps for adjustably supporting said bars on a person's head to thereby retain said undyed strand portion in stretched position to facilitate the dyeing thereof.

9. In a device for hair dyeing as embodied in claim 8, and including the adjacent faces of said pair of elongated bars each having an undulating surface formation, said undulating surfaces being disposed in complementary relatively interengaged arrangement.

40 10. In a device for hair dyeing as embodied in claim 8, and including said pair of elongated bars having a slight arcuate form longitudinally thereof and each bar having an undulating inner face, said undulating faces being disposed in complementary relatively interengaged arrangement.

11. In a device for use in hair dyeing, a pair of elongated bars of non-absorbent material adapted to engage a strand of dyed hair between them to present the new growth of the undyed strand portion between the said bars and the scalp for dyeing thereof, the outer face of each of said bars having oppositely disposed wedge-like formations, a U-shaped clamp slidably forcibly mounted from each end of said pair of bars onto said wedge-like formations for clamping retaining said bars in gripping engagement with the strand of hair, and a pair of screw adjustable supporting members in threaded engagement with said bars, one at one end of one of said bars and the other at one end of the other of said bars, for adjustably supporting said bars on a person's head to thereby retain said undyed strand portion in stretched position to facilitate the dyeing thereof.

12. In a device for use in hair dyeing, a pair of elongated bars of non-absorbent material adapted to engage a strand of dyed hair between them to present the new growth of the undyed strand portion between the said bars and the scalp for dyeing thereof, and a U-shaped

clamps removably secured to and at spaced portions of said bars for clampingly retaining said bars in gripping engagement with the strand of hair.

13. In a device for hair dyeing as embodied in claim 12, and including the adjacent faces of said pair of elongated bars each having an undulating surface formation, said undulating surfaces being disposed in complementary relatively interengaged arrangement.

14. In a device for hair dyeing as embodied in claim 12, and including said pair of elongated bars having a slight arcuate form longitudinally thereof and each bar having an undulating inner face, said undulating faces being disposed in complementary relatively interengaged arrangement.

15. The combination with a pair of spaced elongated clamping means adapted to clampingly engage a strand of hair therebetween including a pair of spaced supports for supporting said means on a person's head, of means for interconnecting said spaced strand-clamping means to facilitate the retainment thereof on the person's head, comprising a pair of clasps adapted to engage said strand-clamping means, and an elongated adjustable connector connecting said

pair of clasps, said connector being adjustable longitudinally thereof to thereby lengthen or shorten same to accommodate said clasps to the spaced distance between said pair of strand-clamping means.

16. In a device for hair dyeing, a pair of bars of non-absorbent material adapted to engage a strand of hair between them, and clamping means adapted to retain the adjacent faces of 10 said bars in pressure-gripping engagement with the strand of hair to prevent seepage of the dye onto the portion of the strand retained between said bars.

17. In a device for use in hair dyeing, a pair 15 of elongated bars of non-absorbent material adapted to engage a strand of dyed hair between them to present the new growth of the undyed strand portion between the said bars and the scalp for dyeing thereof, and clamps at the end 20 portions of said bars for retaining said bars in gripping engagement with the strand of hair to prevent seepage of the dye onto the portion of the strand retained between said bars and for supporting said bars on a person's head to thereby retain said undyed strand portion in stretched 25 position to facilitate the dyeing thereof.

GERTRUDE M. HOFFMAN.
